ATTORNEYS

UNITED STATES PATENT OFFICE.

FRANK ARNOLD BENOLKEN, OF HELENA, MONTANA.

SUPERHEATER CONSTRUCTION FOR LOCOMOTIVES.

Application filed September 12, 1924. Serial No. 737,333.

To all whom it may concern:

Be it known that I, FRANK A. BENOLKEN, a citizen of the United States, and a resident of Helena, in the county of Lewis and Clark 5 and State of Montana, have invented a new and useful Improvement in Superheater Constructions for Locomotives, of which the following is a full, clear, and exact description.

10 My invention relates to improvements in superheater construction for locomotives, and it consists in the combinations, constructions, and arrangements herein described and claimed.

15 An object of my invention is to provide a novel superheater construction for use with a novel type of locomotive driving mechanism, set forth in a companion patent application, Serial No. 737,332, filed Sept. 12,

20 20 A further object of my invention is to provide a superheater construction, in which an economy is effected, due to the utilization of a portion of the combustion chamber for the installation of one of two superheaters, this portion of the combustion chamber being that in which the maximum heat is generated.

25 20 A further object of my invention is to provide a double superheater construction in locomotives, which will give a greater efficiency when used in connection with the novel form of propelling means heretofore mentioned.

30 35 Other objects and advantages will appear in the following specification, and the novel features of the invention will be particularly pointed out in the appended claims.

35 40 My invention is illustrated in the accompanying drawings, forming part of this application, in which—

Figure 1 is a section through a portion of a locomotive, showing the superheaters, and

45 Figure 2 is a view at right angles to Figure 1, showing diagrammatically the steam cylinders.

Referring now to Figure 1, the combustion chamber is shown at 3, surmounted by the crown sheet 4. At 5 I have shown the steam dome. The dry pipe 6 leads from the steam dome.

50 55 The combustion chamber 3 is connected with the smoke chamber 7 by means of the tubes 8, through which the products of combustion pass on their way to the smoke stack 9. The dry pipe 6 has branches 10

and 11, the former leading to the front superheater, and the latter to the rear superheater. Each of these superheaters is provided with pipes 12, through which the steam passes. These are enclosed by larger pipes 13 which serve as return pipes to the steam chambers 14 at the ends of the superheaters. The pipes 13 are disposed inside of the pipes 8, and hence receive the intense heat of the burning gases which are conveyed through the pipes 8.

60 65 In Figure 1, I have shown the steam chamber 14 of the front superheater as being connected by a pipe 15 which runs to the front cylinder 16. A similar pipe 15 also runs to the front cylinder 16 on the opposite side. The steam chamber 14 of the rear superheater is connected in any suitable manner with the rear cylinders shown at 18 70 75 of that type of engine disclosed in my co-pending application. I have indicated this connection diagrammatically by the pipe 17.

75 80 It will be noted that the rear portion of the rear superheater is exposed to the products of combustion in the combustion chamber before they enter the tubes 8. Therefore, a great deal of the heat which would ordinarily pass on through these tubes is imparted to the superheater at this point. 85 The two superheaters are so arranged that they are situated comparatively near to the two sets of cylinders, i. e., the front and rear cylinders on either side. This effects an economy in steam consumption, since it 90 obviates the necessity of transmitting the steam for a considerable distance, and permits it to be utilized immediately.

90 95 It will be observed that the two superheaters are served by the same combustion chamber, the same tubes 8, the same smoke box or chamber 7, and the same stack. The cost of such construction would be less in proportion than the extra power obtained. In addition to this, one of the superheaters, i. e., the rear one, as stated, has the advantage of utilizing the hottest part of the products of combustion.

I claim:

1. A superheater construction for locomotives comprising a front superheater extending into the smoke box, a rear superheater extending into the combustion chamber, and a common set of tubes between said superheaters for conducting the products of combustion.

105 110 115 2. In a device of the type described, a

combustion chamber, a smoke chamber, a smoke stack communicating with said smoke chamber, a steam dome, a front superheater having one end extending into the smoke chamber, a rear superheater having one end extending into the combustion chamber, means for connecting the front end of the front superheater and the rear end of the rear superheater with said steam dome, and 10 pipes common to both of said superheaters for conducting products of combustion from said combustion chamber into said smoke box.

3. In a device of the type described, a 15 combustion chamber, a smoke box, a smoke

stack, a steam dome, tubes extending between said combustion chamber and same smoke box for conducting the products of combustion, a front superheater having one end disposed in the smoke box and having 20 tubes extending rearwardly into said first named tubes, a rear superheater having one end in said combustion chamber and having tubes extending forwardly into said first named tubes, means for supplying steam 25 from said steam dome to each of said superheaters, front cylinders connected with said front superheater, and rear cylinders connected with said rear superheater.

FRANK ARNOLD BENOLKEN.
